UNITED STATES PATENT OFFICE.

JOHN P. DOWD, OF CLEVELAND, OHIO, ASSIGNOR TO THE BROWN HOISTING MACHINERY COMPANY, OF CLEVELAND, OHIO.

MEANS FOR OPERATING SHOVEL-BUCKETS AND SIMILAR RECEPTACLES.

1,008,247.

Specification of Letters Patent.

Patented Nov. 7, 1911.

Application filed July 21, 1911. Serial No. 639,820.

To all whom it may concern:

Be it known that I, JOHN P. Dowd, a citizen of the United States, residing at the city of Cleveland, in the county of Cuyahoga and State of Ohio, have invented a new and useful Means for Operating Shovel-Buckets and Similar Receptacles, of which the following is a full, clear, and exact description, reference being had to the accompanying 10 drawings, forming a part of the specification herewith, wherein similar parts are designated by similar letters in each case.

The device in question, from its nature, is more pertinent to the class of scoops or shovel-buckets used in connection with boom-cranes for excavating or handling material, wherein the bucket proper is pivotally suspended within the bail, at points on its side that are forward of the center of gravity of 15 the bucket when empty, but behind such center when filled, so that when free to move, the bucket will automatically revolve around these points of suspension, discharge its load and immediately right itself into the proper 20 position, with reference to the bail, to take in a new load.

By reason of the manner of poising the bucket-body, within its bail above referred to, tail-latches or corresponding devices, are 30 usual and necessary for their operation, in order not only to preserve a fixed relation between the bucket and the bail while the load is being scooped, but also to prevent a premature discharge of the load as it is being carried around by the crane to the dumping point. It is consequently highly desirable to so contrive and arrange the tail-latching feature of these devices, that the 35 same may be readily unloaded at the will of the operator, and, at any point of its suspension beneath the boom desired.

In the drawings, Figure 1 is a side elevation of an excavating crane with its bucket shown in full lines, upon the material-bed 45 beneath the head of the boom, in position to be hauled in for its load. Dotted lines, in the figure, indicate the several positions the bucket will assume from the time it has gained a load until the same is dumped. 50 Fig. 2 is an enlarged view of the bucket, and associated parts, shown in full lines in Fig. 1. Fig. 3 is a similar view, when the bucket is in position for carrying, with the lower 55 part of the bucket broken away. Fig. 4 is a like view when the bucket is free to dump,

and, Fig. 5 is a broken view of the bail and unlatching features shown in Fig. 2 in the direction of the arrow in that figure.

C represents a boom or excavating crane of an accepted type, and S a shovel-bucket 60 to be operated therewith; L is the usual haul-rope connected at its outer end to the bucket in the manner to be pointed out, and extending backwardly to a controlling drum D on said crane. 65

L¹ is the hoisting-rope whose outer end is connected to the bail and which extends upwardly to and over a sheave V in the head of the boom and thence backwardly to a controlling drum D¹ on the crane. 70

B is the bail. It pivotally engages the sides of the bucket at points t, t, thereon that are forward of the bucket's center of gravity when empty and behind the same when filled. Centrally and at the top of the bail 75 is a rigid clevis E, having upwardly projecting ears R R at the sides thereof, intermediately of which ears, a deep-scored sheave-like member A is mounted upon the transverse center-pin or axle P. As shown, 80 said member is shaped as if oppositely converging segments have been excerpted from the portion thereof that is nearer the front of the bucket when the latter is upright with respect to the bail, and in position for carrying its load as shown in Fig. 3. To this portion a clevis E¹ (to which the outer end of the haul-rope L is fastened) is pivotally connected by a pin P¹. A third clevis E² 85 (to which the outer end of the hoist-rope L¹ is fastened) straddles the ears R, and pivotally engages the pin P exteriorly of said ears. 90

In order to limit the rotary movement of the member A, around the axle P, stops s, s, 95 are provided on each side of said member, near and above the pin P¹, to bring up against the clevis E.

In the flanges on the sheave-member A, on the portion thereof that extends at the rear of the bail when the bucket is in position for carrying, as aforesaid, are elongated slots O, concentric with the score of the sheave-part, to receive and movably support therein a cross-pin p¹ which connects two parallel bars F, F, through their upper ends that overlap said slot for the purpose. 100

The tail-latch proper consists of a bar T whose upper end is pivotally attached, by a pin p, to and between parallel ears R¹ R¹, that 110

are located on the rear of said bail in a vertical plane extending beneath and between the bars F, F. In order to limit and arrest any tendency of the tail-latch bar T to swing beneath the bail when free of its locking engagement with the bucket, the under side of the same near the point of its attachment to the bail, is preferably given a forward horn-like projection n adapted to come up into bearing against the bail under the conditions and with the result referred to. On the same side of said latch-bar, at a suitable point to overhang and engage the rear upper edge of the bucket when the latter is in an upright position within the bail, is a second projection or nose n^1 . The lower end e , of the bar T, extends downwardly and outwardly from said nose or shoulder n^1 at an angle with the upper portion of said bar.

20 The parallel bars F, F, that are hung to the cross-pin p^1 within the slots O, O, as described, extend downwardly, respectively, at each side of the bar T to a point below the inclined portion e , where they are joined together, in a trapeze-like frame, by a cross-roller indicated by r . Here, in order to provide against any undue forward swing of the same, the bars are given sharp upturns f , at each side, to above the bar T, at which point they are connected together by a cross-pin p^2 . As the immediate actuating medium for unlatching the parts described, a tag-line or rope L^2 is fastened, at its outer end, to the pin P^1 , and carried down and around the score in the sheave-member A, and backwardly to a controlling drum D^1 on the crane.

Having thus described a concrete application and embodiment of my invention, its mode of operation will readily be apparent to one skilled in the art to which it belongs. The crane with which the bucket coöperates, being stationed in a working position with its boom approximately above the material through which the scoop is to be made, and the bucket suspended beneath the boom-head, the bucket is lowered into an operative position by simply paying out the hoisting-rope L^1 . In said position the bucket will, of course, be front-down with the latch-bar T locked against the same, and the pull of the haul-rope L will be in substantial alinement with the pivotal points at t and the pin P, as shown in Fig. 2. During the process of lowering, the sheave-member A will have rotated about said pin, and around the pin p^1 in the concentric slots O, without engaging the latter pin, however, or actuating the unlocking bars F. The haul-rope L and the tag-line L^2 may now be wound up, at equal pace, on their respective drums D and D^2 , and, at the same time, the hoist-rope L^1 correspondingly unwound, until the bucket has been dragged inwardly beneath the boom and its fill made. Thereupon, the drum D^2 , controlling the tag-line L^2 , being idle, the drum D, controlling the rope L, is braked, and the hoist-rope L^1 wound in until the pull of the latter rope has so far overcome the resistance of the brake on the drum D and the weight of the bucket and load, as to raise the bucket from its prone position on the material bed, and carry the same upwardly to any desired point beneath the boom. During this operation it is evident that, under the influence of the major force exerted in the direction of the hoist line L^1 , the pull of the haul-rope L will gradually come into direct opposition to that of L^1 , and the sheave-member A, in consequence, will be reversely rotated about the pins P and p^1 , until the end of the slot is brought upwardly, into close proximity to the pin p^1 , as in Fig. 3, so that upon any further rotation of A in the same direction, such end of the slot will engage said pin, and the latter, with the bars F connected thereto, be carried upward thereby. The boom J may now be swung around its center to the place for dumping, the drums D^1 and D^2 , controlling respectively the lines L^1 and L^2 , braked, and, the drum D released. Under these conditions, as is evident, the tension on the rope L will at once be thrown upon and transferred to the tag-line L^2 , that passes around and is fastened to the sheave-member A, and inasmuch as the sheave-member A is free to move around its pivot P^1 , the bucket and load, with all the connected parts, will swing downwardly on the rope L^1 , around the boom-head as a center. Under such conditions the sheave-member A, under the tension of the tag-line L^2 , will revolve upwardly from its position in Fig. 3, to that shown in Fig. 4, and during this movement, the end of the slots O will engage and carry upward the pin p^1 , and the bars F, F, connected thereto, whereby the roller r will be drawn up beneath the inclined portion e until it lifts the nose n^1 out of engagement with the bucket. The bucket will at once automatically revolve about the trunnions or pivot points at t , and the dump be made.

What I claim and wish to protect by Letters-Patent is:

In a boom-crane or similar hoisting apparatus, having oppositely related hoisting and hauling ropes, the combination, with a shovel-bucket or similar receptacle pivotally suspended within a bail at points on the sides thereof that are forward of the center of gravity of the bucket when empty, and behind said center when loaded, of a latch-bar pivotally connected to said bail at its upper end and projecting outwardly and downwardly, at an angle, at the other end, said latch-bar being of suitable form and dimensions to overhang and engage said bucket when the latter is upright with re-

spect to said bail, a sheave-like member revolvably mounted above and transversely of said bail, an unlocking-bar pivotally connected at its upper end to said member in 5 a suitable manner to be engaged thereby and carried upwardly to a predetermined degree in a direction concentric of the axis of motion of said member when the latter is revolved upwardly around said axis, and to 10 permit said member to be revolved in the contrary direction without thereby engaging and moving said unlocking bar with relation to said latch-bar, said unlocking bar extending downwardly to and beneath the project- 15 ing end of said latch-bar, together with a rope attached to and reeved around said member at its outer extremity, and extend-

ing backwardly therefrom and connected to a controlling drum on said apparatus provided for the purpose, a haul-rope connected 20 to said member and extending backwardly therefrom and connected to a similar drum, and a hoist-rope connected to said bail at the center or axis of revolution of said member and extending to and around a 25 sheave at the head of the boom on said apparatus and thence backwardly and connected to a similar drum, substantially as shown and described.

JOHN P. DOWD.
